INVENTOR
John Quern
BY
Mark D. Orlansky, Attorney

UNITED STATES PATENT OFFICE.

JOHN QUEEN, OF BROOKLYN, NEW YORK.

ELECTRIC HOT-AIR FURNACE.

Application filed February 25, 1928. Serial No. 256,834.

This invention relates to electric hot air furnaces and has for its object to provide a construction that will be suitable for private houses, apartments etc., to be used in lieu of 5 coal furnaces or oil burners.

Another object of this invention is to provide an electric furnace which will be simple, cheap and effective.

A still further object is to provide a construction that can be conveniently transported, and taken apart for cleaning or repair work.

And still a further object is to provide means that will enable the regulation of the 15 temperature within certain limits.

With these and other objects in view my invention substantially consists in the novel construction, combination and arrangement of parts as will be hereinafter more fully 20 described and defined in the appended claims.

In the accompanying drawing which forms part of this specification and in which similar reference characters denote corresponding parts, Fig. 1 is a vertical section of my 25 new electric hot air furnace; Fig. 2 a cross section on line 2—2 of Fig. 1 and Fig. 3 a dia- grammatic view of the heating elements and the switch for controlling the same.

In the drawing 10 denotes a substantially 30 circular open base formed with a number of feet 10' to support the same at an elevation from the ground or floor. The base is pro- vided on its upper face with an annular groove 10². Centrally extending through the 35 base and suitably supported is a vertical post 11 on which are mounted in vertically super- posed position two horizontally arranged star shaped or multi-armed members 12, 12'. The arms 12² of the two members are in alinement 40 above one another and fixed to each two cor- responding arms 12² is a coil resistance 13 suitably insulated from said arms. Fixed to the post 11 below the lower member 12' is an arm 14 which carries a number of contact 45 points 15 to which all resistances are conductively connected and which are adapted to be suitably connected to one pole of an electric source (not shown) as the house lighting system. Rotatively supported on the base 50 10 is a manually operable arm 16 which has a contact member 16' adapted to be conductively connected to the other pole of said electric source, and which in cooperation with the contact points 15 constitutes a manual 55 switch for regulating the heating unit. Ac- cording to the diagram of the present exam-

ple three resistances 13 are connected in parallel electrically to constitute a single unit so that by moving the switch onto one of the extreme end contact points the circuit will 60 be closed through said three resistances. One or more resistances can be added by turning the switch successively to the other contact points. 17 denotes a tubular or cylindrical mantle of suitable heat insulating material 65 which preferably is composed of individual separable sections or segments 17', 17² etc. These sections are borne in the annular groove 10² and adapted to engage a similar groove 18' in a lid or cover 18 of similar heat insu- 70 lating material. This lid which is arranged above the heating unit is adapted to close the mantle on top and is provided with one or more air passages 18². When the furnace is to be used for different rooms of an apart- 75 ment or floors of a private house pipes 19 may be provided to communicate with said passages to convey the hot air to the different places. The cool air of the room in con- tinuously circulating through the space be- 80 tween the heating elements will be very rap- idly heated.

Since various changes may be made in the construction without departing from the principle of my invention, I do not wish to 85 restrict myself to the details shown and de- scribed.

What I claim is:

1. An electric hot air furnace, comprising an open base adapted to be supported at an 90 elevation from the ground, a sectional mantle supported on said base, a lid removably borne on top of said mantle and holding the sections together, a plurality of cylindrical electric heating coils vertically supported on said 95 base so as to form a central air space between themselves and means for connecting said electric coils with an electric source, said lid having a number of air passages for the attachment of pipes leading to different places. 100

2. An electric hot air furnace, comprising an open base having feet and formed with a marginal annular groove, a mantle of heat insulating material composed of separable sec- 105 tions borne in said groove, an electric heating unit comprising two vertically superposed multiarmed members supported on said base and electric coils insulated from one another and extending vertically between correspond- ing arms of said two members, stationary con- 110 tact pieces at the base connected to one pole of an electric source and to which said coils

are conductively connected, a switch for said electric unit mounted on said base consisting of a manually operable arm having a contact member connected to the other pole of said 5 electric source and adapted to cooperate with said first named contact pieces, and a lid of heat insulating material formed with an annular groove to engage the upper edges of the mantle and closing the top of the latter, 10 said lid having air passages for attachment of hot air pipes leading to different places.

3. An electric hot air furnace comprising an open base having feet, and formed with a 15 marginal annular groove, a mantle of heat insulating material composed of separable

sections borne in said groove, an electric heating unit comprising two vertically superposed multiarmed members supported on said base, electric heating coils, insulated from one another and extending vertically between corresponding arms of said two members, and mounted thereon, a lid of heat insulating material formed with an annular groove to engage the upper edges of said mantle and close the top of the latter, said lid having air passages for attachment of hot air pipes and means for electrical connection to said heating coils. 20 25

In testimony whereof I affix my signature.
JOHN QUERN.
